CLAIM

The ornamental design for a can, substantially as shown and described.

DESCRIPTION

FIG. 1 is a perspective view of a can embodying our new design;

FIG. 2 is a side elevational view of the container of FIG. 1;

FIG. 3 is a bottom plan view of the container shown in FIGS. 1 and 2; and,

FIG. 4 is a top plan view of the container shown in FIGS. 1 and 2.

The characteristic feature of our design resides in the combination on the disclosed container of the vertical embossments around the side walls.

FIG. 1

FIG. 2

FIG. 3

FIG. 4
